(57) **CLAIM**

The ornamental design for an applicator, as shown and described.

DESCRIPTION

FIG. 1 is a perspective front view of an applicator embodying the new design shown;

FIG. 2 is a front view of the design shown in FIG. 1;

FIG. 3 is a left side view of the design shown in FIG. 1;

FIG. 4 is a back view of the design shown in FIG. 1;

FIG. 5 is a right side view of the design shown in FIG. 1;

FIG. 6 is a bottom view of the design shown in FIG. 1; and,

FIG. 7 is a top view of the design shown in FIG. 1.

The dash-dash lines shown in the figures described above illustrate the portions of the applicator that form no part of the claimed design.
